[54] LAWN CHAIR

[75] Inventor: Edward Secon, Trumbull, Conn.[73] Assignee: The Sherwood Corporation, Spring City, Tenn.[21] Appl. No.: 266,940[22] Filed: May 26, 1981[51] Int. Cl. .... D6—01[52] U.S. Cl. D6/37; D6/70;
..... D6/77[58] Field of Search D6/37-39,
..... D6/47-78

[56] References Cited

U.S. PATENT DOCUMENTS

D. 239,990 5/1976 Olko ..... D6/57D. 241,093 8/1976 Olko ..... D6/57D. 257,573 12/1980 Hanaford ..... D6/77 XD. 266,639 10/1982 Thorpe ..... D6/57 X2,623,574 12/1952 Damsch ..... D6/37 X3,742,526 7/1973 Lillard ..... D6/37 X
3,751,739 8/1973 Assmann ..... D6/37 XPrimary Examiner*—Bruce W. Dunkins*Attorney, Agent, or Firm*—Alan Ruderman

[57] CLAIM

The ornamental design for a lawn chair, substantially as shown and described.

DESCRIPTION

FIG. 1 is a front perspective view of a lawn chair embodying my new design;

FIG. 2 is a rear perspective view of the lawn chair with the cushion pad removed for convenience of illustration;

FIG. 3 is a front perspective view of the lawn chair similar to FIG. 1, but with the leg support members extended for use as a chaise lounge;

FIG. 4 is a view similar to FIG. 3 illustrating the cushion pad in a partially unfolded condition; and

FIG. 5 is a view similar to FIG. 4 with the cushion pad unfolded to the chaise lounge condition.

FIG. 1

FIG. 2

FIG. 3

FIG. 4

FIG. 5